DEVICE FOR CONTROLLING THE LOAD
OPENING IN BOXCARS AND THE LIKEArthur Weisz, Bratislava, Czechoslovakia, assign-
or to Leo Feuer, New York, N. Y.

Application December 2, 1937, Serial No. 177,668

8 Claims. (Cl. 20—32)

The present invention relates to a device for controlling the load opening in the wall of a box car or the like. Box-cars and similar vehicles are conventionally equipped with sliding doors or with doors hinged to the frame of the load opening in the wall of the vehicle. Such doors are usually so arranged as to cover the openings at the outside of the respective wall. However, doors of the mentioned type are not serviceable if the car is to be used for the transportation of goods in bulk, particularly of granular goods, such as grain, frequently requiring a tight sealing of the load opening substantially up to the level of the goods, and at least some free opening above said level.

The object of the present invention is to provide a device which may be mounted within a box-car or the like, either removably or for good, and which permits to close the load opening up to the required limit.

A further object of the invention is to provide a device for the said purpose, which may be used either instead of or in addition to the conventional doors present in a car.

Another object of the invention is to provide a device for the said purpose, which does not or at least only incon siderably reduces the loading space of the vehicle to which said device is applied.

The invention essentially comprises two guide rails laterally of the load opening and a plurality of individual boards of wood or other suitable material, said boards fitting one upon the other one with their horizontal edges and being guided by said rails and adapted to be moved vertically in the rear of the load opening.

The invention further consists in means for arresting said boards when lifted beyond a pre-determined level, and in a cover-provided aperture in one or several of said boards. Such apertures serve to partially discharge the goods and to release the pressure of the goods against said boards prior to the complete discharging.

Further objects and details of the invention will be apparent from the description hereinafter and the accompanying drawings illustrating an embodiment thereof by way of example.

In the drawings

Fig. 1 shows a longitudinal section of a railroad box car equipped with the device according to the invention.

Fig. 2 is a section along line 2—2 of Fig. 1.

Fig. 3 is a partial section along line 3—3 of Fig. 2 on a larger scale.

Fig. 4 shows a vertical section taken on the line 4—4 of Fig. 3 of one of the boards.

Fig. 5 is a side view of parts, partly in section taken on the line 5—5 of Fig. 3.

Fig. 6 is a sectional view of a modification of parts similar to Fig. 3.

Figs. 7 and 8 are elevations of a portion of a rail with board-arresting means, a board being shown in two different positions respectively, and

Fig. 9 is a section along line 9—9 of Fig. 8.

Fig. 10 is a section similar to Fig. 3, of a modification.

Fig. 11 is a vertical section, in part, of a car with the modification of Fig. 10.

In order to illustrate my invention, I have shown a railroad box car of conventional design, which is equipped with the new device. The same device may be used with equal result in vehicles of any kind, as for instance in trucks, in which the load varies as to its character. In the drawings, the box car 1 comprises two longitudinal side walls 2 and 3 with load openings 4 and 5 respectively therein. 6 is the top of the car, and 7 a conventional sliding door which may be shifted in front of opening 4 or aside to permit loading and discharging. The sliding door of opening 5 is denoted by 8. It is obvious that a car provided with sliding doors in front of the load openings is not useful for the transportation of granular goods such as grain, because, on the one hand, the car could not be loaded to its carrying capacity, and because, on the other hand, grain would continuously pour out through the gaps between the doors and the car walls.

The new device for adapting the car for the requirements of transportation of goods in bulk, particularly of grain, comprises two guide rails 9 and 10 of any suitable cross-section, laterally of the opening 4. In the embodiment of Figs. 1 to 3, the rails are arranged within the car and are attached by suitable means to wall 2. The connection between the rails and the car wall may be performed by screws 11 in order to permit easy removal of the entire device when not in use. The rails have a curved portion 12 near the corner between the wall 2 and the top 6 of the car and a substantially horizontal portion 13 beneath the car top. If, as shown in the example of Fig. 2, there are two opposite load openings 4 and 5 in the walls 2 and 3 respectively, the rails may be continued along the sides of opening 5, to form an inverted U mounted on the floor 50 of the car.

Coordinated to each opening is a plurality of

boards 14 in guiding engagement with rails 9 and 10. The boards are so arranged as to fit one on top of the other one with their horizontal edges, and there are so many boards of such individual heights that the total height of the boards is at least slightly higher than the maximum load level of the granular goods. The length of the boards may be slightly greater than the width of opening 4 in order to permit tightening of gaps between the boards and the rails. Near their ends, the individual boards 14 are provided with means for engagement with rails 9 and 10. Said means may consist in hook-like projections 15 secured to boards 14 and engaging the channels of rails 9 and 10 as clearly shown in Fig. 3. Thus guided, the boards may be individually shifted upward from their position as shown for those of opening 4 at the left hand side of Fig. 2, to a position below the car top 6 as shown with respect to the boards 14 of the right hand side of Fig. 2. In order to permit an easy passage of the boards through the curved rail portion 12, hooks 15 are of such height that there is a certain gap between the boards and the rails when the hooks engage the inner flank of the rails. This gap also permits that the boards may be shifted with very little friction. In order to decrease still more the frictional resistance, hooks 15 may be provided with anti-friction rollers 16 as shown in Fig. 5. The said gap, however, would be objectionable at the lower portion of rails 9 and 10 up to the height to which granular goods may be loaded. For this reason fillers 17 are provided which are tapered at their upper ends 18 to permit the boards to mount these fillers when the boards are lowered from their position below the car top. The friction between the boards and the fillers prevents shaking of the boards and undesired lifting owing to road shocks. The closing of the gap at the lower portion of rails 9 and 10 may also be performed by other means as for instance shown in the modification of Fig. 6, in which channels 19 and 20 are provided at the rail 9 and board 14. A rod 21 of suitable cross-section may be loosely inserted from above between channels 19 and 20. The pressure of the granular goods will urge parts 19, 20 and 21 tightly together to prevent any leakage.

In order to prevent leakages through gaps between two adjacent boards, a strip 22 preferably of a flexible material, may be provided near the lower edge of the upper one of two adjacent boards. Strip 22 is sufficiently wide to overlap the upper edge of the lower one of the adjacent boards. The pressure of the goods will then bend the strip into engagement with the lower board to close any existing gap.

Each board 14 may be provided with handles 23 to facilitate the shifting of the boards along rails 9 and 10. At least the lowest of the boards has, preferably, an aperture 24, closed by a slide 25 at the outside of the board. Slide 25 is movable in guides 26, so that aperture 24 may be opened for a purpose described hereinafter. Other boards or even all of the boards may have similar openings with slides.

Means for stopping the boards in their position near the car top may be provided as indicated at 27 in Fig. 2. In the preferred form of Figs. 7 and 8, such means comprise a hook-shaped member 28 and a wedge shaped part 29 both attached to the rail 9. Similar members may be also attached to rail 10. Wedge 29 has a downwardly inclined slope 30 and a steep face 31, and is

arranged within the rail channel. The hook-shaped member 28 projects, outside of the rail, towards the path of the boards 14. The latter are provided with projections 32 so formed as to pass through the opening of hook 28 when the pertaining rail-engaging member 15 rides upward slope 30, and to be located below hook 28 when member 15 has dropped from said slope to bear against face 31.

The device according to the invention operates in the following manner. In order to load the car with goods in bulk, boards 14 of all loading openings are brought into the position as shown at the left-hand side of Fig. 2 with slides 25 in front of the apertures 24, and the lowest board 15 resting on the floor of the car. The goods in bulk are loaded through the free portion of opening 4 up to the required level which is below the upper edge of the topmost board 14. The pressure of the goods will urge the flexible strips 22 to bear against the boards and to close gaps therebetween. Similarly, the boards are pressed against fillers 17 attached to rails 9 and 10, to prevent any leakage between the boards and the rails. If there is a sliding or other door present at the outside of the car, such door may be closed and sealed after the loading is completed.

In order to discharge the load, first, the outside doors if present are to be opened. Thereafter, the slides 25 are removed from apertures 24 to permit a partial discharge of the granular goods. Simultaneously, the pressure of the goods against the boards decreases. When the pressure is sufficiently reduced the topmost board may be lifted and pushed upwards until its lower rail-engaging hooks 15 have travelled over slopes 30, and its projections 32 have passed the stop hook 28. Fig. 8 shows a board 14 with its lower (right hand) hooks 15 on the slope 30 and its projection 32 about to pass hook 28. After having entirely passed the hook 28 and being let loose, the board will slide back on the curved portion 12 of the rails until the rail-engaging hooks 15 bear against the faces 31 of wedges 29, and projections 32 are in the position relative to hooks 28 as indicated in Fig. 7. As soon as the pressure of the load against the lower boards has sufficiently decreased, one board after the other may be pushed upward in the same manner thereby advancing the preceding board or boards along the substantially horizontal rail portions 13. When the originally lowest board is stopped behind the wedges 29, the load opening 5 is entirely free and the car may be completely discharged, as shown in Fig. 2.

With all boards below the top of the car in the position as indicated in the right hand part of Fig. 2 the device occupies almost no space at all which otherwise may be useful as loading space if the car is to be used for goods other than goods in bulk. If between two successive charges of goods in bulk a long period of time is intermittent in which the car must be used for other purposes, the device according to my invention may be easily removed by unscrewing the screws 11 with which the rails 9 and 10 are secured to the framework of the car. The same device may also be alternately used for different cars of equal widths of their load openings. The new device is particularly useful in the transportation of goods in bulk and granular goods such as grain. It may be used with advantage also in the transportation of animals such as cattle or horses, and of loads requiring much ventilating air.

In the modification illustrated by Figs. 10 and 75

11, the rails 35 and 36 are parts of the car structure proper, in fact they form the posts of the load opening 37 with their vertical portions, and the roof-beams with their upper substantially 5 horizontal portion. A wedge piece 38 fills the corner between the roof, the wall and the curved portion of the rails. In all other respects the device is the same as hereinbefore described.

Many alterations and modifications of the illustrated form of my invention will be apparent to those skilled in the art, and may be practiced without departing in any way from the scope of my invention.

What I claim is:

15 1. A device for controlling the load opening in the wall of a box car and the like, to adapt it for the transportation of goods in bulk, comprising guide rails adapted to be secured to a car laterally of its load opening each rail including 20 at least two flange surfaces parallel to each other and to the plane of the load opening, a first one of said flange surfaces facing the inside of the car, and a second one facing the outside of the car, a plurality of individual boards fitting one 25 upon the other with their horizontal edges, said boards being adapted to engage with their outer surfaces portions of said first flange surfaces, and to be moved vertically in the rear of said opening so as to close at least the lower portion 30 of said opening when lowered, and rail-engaging members secured to said boards and adapted to engage said second flange surfaces.

2. A device for controlling the load opening in the wall of a box car and the like to adapt it for 35 the transportation of goods in bulk, comprising guide rails adapted to be secured to a car laterally of its load opening, said guide rails including flange surfaces facing the inside of the car, a plurality of individual boards fitting one upon the 40 other with their horizontal edges, said boards being guided by said rails and adapted to be moved vertically in the rear of said opening so as to close at least the lower portion of said opening when lowered, said boards being so arranged 45 relatively to said rails as to be pressed by a load of bulk in the car with their outer surfaces against said flange surfaces, and strips of flexible material attached to the inner surfaces of said boards near their lower edges and adapted to overlap the 50 upper edges of the adjacent boards respectively.

3. A device for controlling the load opening in the wall of a box car and the like to adapt it for the transportation of goods in bulk, comprising guide rails adapted to be secured to a car laterally of its load opening, said guide rails extending substantially from the bottom of the car upward and at least partly across the car near its top, a plurality of individual boards fitting one upon the other with their horizontal edges and having 55 a length greater than the width of said opening, said boards being guided by said rails and adapted to be moved vertically in the rear of said opening so as to close at least the lower portion of said opening, when lowered, and to give substantially 60 the entire opening free when raised and moved along said rails below the top of the car, and means for closing gaps between said boards and said rails near the lower portion of said opening,

comprising first channel-shaped members along the lower portion of said guide rails and second channel-shaped members along the outer face of said boards opposite said first members, and elongated members adapted to be inserted into 5 the hollow spaces of the opposed first and second channel-shaped members.

4. A device for controlling the load opening in the wall of a box car and the like to adapt it for the transportation of goods in bulk, comprising 10 guide rails adapted to be secured to a car laterally of its load opening, each rail including at least two flange surfaces parallel to each other and to the plane of the car opening, a first one of said flange surfaces facing the inside of the 15 car, and a second one facing the outside of the car, a plurality of the boards fitting one upon the other with their horizontal edges, said boards being adapted to engage with their outer surfaces portions of said first flange surfaces, and to be 20 moved vertically in the rear of said opening so as to close at least the lower portion of said opening, rail-engaging members secured to said boards and adapted to engage said second flange surfaces, the distance of said rail-engaging members 25 from the outer surfaces of their associated boards being so selected as to prevent said members and boards from simultaneously engaging said rails, and fillers attached to the lower portions of one of said flange surfaces for closing gaps between 30 said rails and said boards when the latter are lowered.

5. A device as claimed in claim 4 in which said fillers are wedge-shaped at their upper ends.

6. A device as claimed in claim 4 in which said 35 rail-engaging members include anti-friction rollers, the diameter of said rollers being so selected that the latter do not engage said rails when the 40 outsides of the boards are in engagement therewith.

7. A device as claimed in claim 1 in which each board is provided with four rail-engaging members, one near each of the corners of the board, each member having a rail-engaging portion in spaced relation to the outer surface of the associated board, whereby a portion of one of said 45 rails may enter the gaps between said rail-engaging portions and associated board, said gaps being sufficiently wide to permit said boards to pass curves of said rails.

8. A device for controlling the load opening in the wall of a box car and the like to adapt it for the transportation of goods in bulk, comprising guide rails adapted to be secured to a car laterally of its load opening, each rail including a 55 flange parallel to the plane of the car opening and being directed towards the flange of the opposite rail, a plurality of individual boards fitting one upon the other with their horizontal edges, said boards being adapted to engage with their 60 outer surfaces portions of the inner surfaces of said flanges, and to be moved vertically in the rear of said opening so as to close at least the lower portion of said opening when lowered, and rail-engaging members secured to said boards 65 and adapted to engage the outer surfaces of said flanges.

ARTHUR WEISZ.
